PROCESS FOR TREATING ORGANIC COMPOUNDS BY ELECTROLYSIS.

1,225,052.

Specification of Letters Patent.

Patented May 8, 1917.

Application filed December 31, 1915. Serial No. 69,624.

To all whom it may concern:

Be it known that I, Dr. ALFRED PIGUET, chemist, a citizen of the Swiss Republic, and resident of Basel, Switzerland, have invented a new and useful Process for Treating Organic Compounds by Electrolysis, of which the following is a full, clear, and exact specification.

The electrolytic treatment of organic compounds, in order to subject the same to a reduction or to an oxidation, is generally effected by emulsifying the organic body in the electrolyte and subjecting the emulsion to the action of the electric current at the cathode or the anode (active electrode). In order to obviate the disturbing influence of the other electrode, that is to say of the electrode of opposed polarity, hitherto either diaphragms were interposed between both the electrodes or very high densities of current were employed at the said electrode of opposed polarity.

I have now found that the disturbing influence of the said electrode can still be minimized by preventing the emulsion from reaching this latter electrode. This result is easily obtained by the difference of the specific gravity of the electrolyte and of the specific gravity of the organic body to be electrolyzed or of the solution of this latter in an indifferent solvent unmixable with the electrolyte. If care be taken to choose the said difference of specific weights sufficiently great, it becomes easy to produce in the neighborhood of the active electrode a good emulsion which does not reach the other electrode.

The new process is illustrated by the following examples; reference being made to the accompanying diagrams:

Figure 1 is a view, in section, of a form of apparatus in which the outer vessel acts as an anode, while an inner vessel serves as a cathode; Fig. 2 is a view, in section, of a form of apparatus in which the cathode is at the top and the anode at the bottom; Fig. 3 is a view, in section, of a form of appara-

tus in which the anode is at the top while the cathode is at the bottom.

Example 1.

Reduction of nitrobenzene to azobenzene.

Into the middle part of a vessel of iron, having the form of a truncated cone (Fig. 1), which serves also as anode and has a conical bottom lined with a layer of cement *c*, is placed a cylinder *k* formed by several layers of iron-wire trellis acting also as cathode. The whole apparatus is filled up with soda lye of 2 to 5% and with nitrobenzene, which latter sinks to the bottom of the recipient by reason of its higher specific gravity. A small rotatory pump *p* turning at a high speed causes the formation of the emulsion and the slow circulation through the cylindrical cathode. At the bottom of the vessel collects a mixture of azobenzene and nitrobenzene, which is maintained continuously in circulation by the pump. The reduction is achieved when all nitrobenzene has disappeared. The electrolysis is effected with 10 amperes per square decimeter and 2.5 to 3 volts at 85 to 95° C.

Example 2.

Preparation of hydrazobenzene from azobenzene.

Into a vessel *c* (Fig. 2) of cement or other convenient material, is introduced at first soda lye of 30° Bé. gravity, in which some lead oxid has been dissolved, and afterward a solution of azobenzene in a solvent, as for instance benzene. This solution floats on the surface of the soda lye. The anode *a* is placed in the lower part of the vessel. At a distance of about 20 centimeters above the said anode is placed the cathode *k* formed for instance by iron-wire trellis. The cathode must be placed at the limit of the two liquids (soda lye and solution of azobenzene). By a convenient vibrating movement of the cathode *k* the emulsion of the azobenzene solution into the soda lye is pro-

duced. This vibrating movement is regulated in such a manner that the emulsion layer formed at the cathode is not too strong, nor too feeble. A too strong emulsion would produce an elevation of the voltage and a too feeble emulsion would produce losses of hydrogen. The electrolysis is effected at about 90° C. with a current density of about 3 amperes per square decimeter and a tension of 3 to 4 volts, until all the azobenzene is transformed into hydrazobenzene. It is of advantage to collect the oxygen evolving at the anode by convenient means for instance by a wire trellis disposed above the anode in such a manner that the oxygen cannot rise to the cathode.

When the specific gravity of the electrolyte is lower than that of the emulsion, the position of the electrodes would be inverted.

20 *Example 3.*

Preparation of hydrazobenzene from nitrobenzene.

In the electrolyzer of Fig. 2, the electrodes are inverted in such a manner that the anode comes above the cathode. As electrolyte a solution of 2 kg. lead oxid in 800 liters soda lye of 20° Bé. is charged into the electrolyzer, and afterward a solution of 123 kg. nitrobenzene in 250 liters of an indifferent solvent of a high specific weight, for instance of dichloronaphthalene, is added. This latter solution collects at the bottom of the vessel. The cathode placed near the solution of nitrobenzene is put into vibration, whereby the required emulsion is produced. The electrolysis is effected at a temperature of 85 to 95° C. The nitrobenzene is smoothly reduced to hydrazobenzene. The current density is 3 amperes per square decimeter and the current tension 2.5 to 3.5 volts. With 1000 amperes the reduction lasts 120 to 150 hours. The yields are 85 to 95% of the theoretical.

45 *Example 4.*

Preparation of hydrazotoluene.

In a square box of cement *c* (Fig. 3) are disposed horizontally two electrodes of metallic trellis, at a distance of about 20 centimeters each from the other. The upper electrode *a* serves as anode and the lower electrode *k* as cathode. The apparatus is charged with a solution of soda lye of 10-15 per cent and a mixture of orthonitrotoluene with an indifferent solvent of a high specific weight, so that the said mixture sinks to the bottom of the apparatus.

60 By a convenient stirring, for instance by producing a circulation by a rotary pump, the emulsion is obtained. The electrolysis is effected at 80 to 100° C. The reduction is

quantitative in presence of oxids soluble in alkalis, as for instance PbO, ZnO, SnO, etc. 65 The density of the employed current is 4.5 amperes per square decimeter and its tension 2.5 to 3 volts.

Naturally in each of the foregoing examples, the reduction can if desired be 70 driven beyond the formation of the azo step or it can be interrupted before the hydrazo step is attained.

The same process can be employed for the oxidation of organic substances, as shown 75 by the following example:

Example 5.

Oxidation of isoborneol to camphor.

80 Into an apparatus according to Fig. 2, in which *k* designates the anode and *a* the cathode, are introduced a solution of 200 gr. potassium permanganate in 10 liters soda lye of 10 per cent, and a solution of 3 kg. 85 isoborneol in 5 liters benzene. The solution of isoborneol floats on the other solution. The anode *k* placed near the solution of isoborneol can be made of lead. By putting the same into vibration, the required emulsion 90 is produced. The electrolysis is effected at a temperature of 15 to 20° C. with a current density of 0.5 ampere per square decimeter at the anode, until the solution, which first became green in consequence of the formation of manganate, turns again to violet. 95

What I claim is:

1. The described process for treating organic bodies by electrolysis, consisting in 100 charging into an electrolyzer an electrolyte and the liquid organic body to be electrolyzed showing such a difference of specific gravities that near the active electrode a sufficient emulsion can be produced, which cannot reach the other electrode, producing 105 such an emulsion and electrolyzing the contents of the electrolyzer in the usual manner.

2. The described process for treating organic bodies by electrolysis consisting in 110 charging into an electrolyzer an electrolyte and a solution of the organic body in an indifferent solvent not mixable with the electrolyte, the said electrolyte and solution of the organic body showing such a difference of their specific gravities that near the active 115 electrode a sufficient emulsion can be produced, which cannot reach the other electrode, producing such an emulsion and electrolyzing the contents of the electrolyzer in the usual manner.

3. The described process for treating organic bodies by electrolysis, consisting in 120 charging into an electrolyzer an electrolyte and the organic body to be electrolyzed having such a difference of specific gravities 125 that a sufficient emulsion can be produced in

the neighborhood of the active electrode which cannot reach the other electrode, putting the said active electrode into vibration in order to produce such an emulsion and electrolyzing the contents of the electrolyzer in the usual manner.

4. The described process for treating organic bodies by electrolysis, consisting in charging into the electrolyzer an electrolyte 10 and a solution of the organic body in an indifferent solvent not mixable with the electrolyte, showing such a difference of specific gravities, that a sufficient emulsion can be

produced near the active electrode which cannot reach the other electrode, putting 15 the said active electrode into vibration in order to produce such an emulsion and electrolyzing the contents of the electrolyzer in the usual manner.

In witness whereof I have hereunto signed 20 my name this 13th day of November, 1915, in the presence of two subscribing witnesses.

DR. ALFRED PIGUET.
